DRY SHAVER

Reinhard Willem Jacob Veersema, Eindhoven, Netherlands, assignor to North American Philips Co., Inc.

Filed July 13, 1959, Ser. No. 56,758

Term of patent 14 years

(Cl. D22—3)

FIG.1

FIG.2

FIG.3

FIG.4

FIG.5

FIG.6

Fig. 1 is a side perspective view of a dry shaver showing my new design;

Fig. 2 is a side elevational view thereof;

Fig. 3 is a rear perspective view;

Fig. 4 is a side elevational view of the side opposite that shown in Fig. 2;

Fig. 5 is a front elevational view; and

Fig. 6 is a top plan view thereof.

I claim:

The ornamental design for a dry shaver, as shown.
